Claims priority, application France Dec. 15, 1955

5 Claims. (Cl. 62—28)

This invention relates to a process for the separation of air at low temperatures.

Previously compressed air is cooled and purified, at least in part, in an exchange apparatus, the gas streams reversed periodically, and the compressed air is then rectified in at least two columns operating at different pressures with mutual heat exchange. A principal purpose is to eliminate beforehand the high boiling impurities of air, like water vapor and CO₂, simply by cooling them.

If a reversing or a regenerating exchanger is used for cooling air beforehand, or if the air stream going in and the gas stream going out succeed each other periodically in the same pipe, complete evaporation by the separated gas of the impurities deposited as solids by the air can only be assured under certain conditions. For example, the average throughput of gas passing through the cold portion of the exchanger in the opposite direction to air must exceed the average throughput of air, so that the difference in temperature between the air and the gas at the cold end of the exchanger is not too great.

To accomplish this, it has already been proposed, in a two-column rectification plant, to lead a stream of nitrogen through a special pipe, from the upper part of the high-pressure column, through the exchange apparatus, in a direction opposite to that of the air going in, to compress this nitrogen, to liquefy it by heat transfer, and to use it as the reflux liquid. However, this method has the disadvantage that it does not improve appreciably the separation carried out in the low pressure column.

A novel feature of the present invention is that the recycled nitrogen gas is withdrawn from the low-pressure column.

This arrangement overcomes the inconvenience stated above and presents the advantage of increasing the flows of reflux liquids in the rectification unit thereby improving the separation. When a fraction of the air leaving the heat exchange apparatus is sent to an expansion machine, the compressed nitrogen can be used to warm this fraction before expanding it.

The compressed nitrogen can also be used to heat the products of separation—oxygen and nitrogen—extracted from the lowest pressure column before they reach the exchange apparatus used for the initial cooling of the air.

Finally, the compressed nitrogen can also be used to heat the highest pressure column, and all or at least a major part of it can be liquefied as a result. This arrangement is advantageous because it allows the introduction of compressed and cold air not at the bottom of the highest pressure column, but appreciably higher up, so that the liquid descending from the level of the air feed is enriched in oxygen. Thus, a liquid appreciably richer in oxygen than it would be, were it in equilibrium with atmospheric air, can be sent to the lowest pressure column. Separation is thus improved.

2

The nitrogen compressed and liquefied according to this invention will be preferably introduced at the top of the lowest pressure column, while liquid nitrogen, coming from at least one of the higher pressure columns, will be preferably introduced lower than the said top. This arrangement is particularly advantageous in the case where two nitrogen gas streams at low pressure are to be produced, one in a relatively impure state to be released as waste to the atmosphere after heating in the proper exchangers, and an essentially pure nitrogen product, a part of which is compressed and liquefied in accordance with the invention.

The various improvements of this invention are described in the following example and illustrated in the attached schematic drawing representing a two-column plant for air fractionation wherein they are used in continuation.

The air to be treated, compressed under a pressure of 6 kg./cm.² and at about 30° C., flowing through pipe 1 and reversing-valve 2, enters reversing-exchanger 3 where it passes either through the segment represented by pipe 4, or in the space surrounding the other segments, according to the position of reversing-valves 2 and 2A.

25 In this exchanger, the following gases flow counter-current to the air:

(a) Impure nitrogen flowing either in the space surrounding the segments, if the air is flowing through segment 4, or in segment 4 if the air is flowing in the space 30 surrounding the segments;

(b) Oxygen flowing in the segment represented by pipe 5, and

(c) Pure nitrogen flowing in the segment represented by pipe 6. A part of this pure nitrogen can leave the 35 exchanger, after passing through its cold section through valves 37 and pipe 37A.

The air, leaving the exchanger at about -171° C., flows through reversing-valve 2A and pipe 7. Then it divides into two parts: one, flowing through pipe 8, 40 enters high pressure column 15 a few plates above its bottom, under a pressure of about 5.8 kg./cm.²; the other part flows through valve 9, pipe 9A, and exchanger 10 where it is warmed by heat transfer with the pure and compressed nitrogen to about -150° C. Then this air 45 is expanded in turbine 11 to about atmospheric pressure. The discharge temperature of the turbine is approximately -187° C.

To improve the operation of low-pressure column 16—17, a part of the air leaving turbine 11 can be sent 50 in a variable quantity through valve 13 into pipe 13A and exchanger 14, where it is warmed to about -173° C.—substantially the temperature of the cold end of the exchanger—by indirect heat exchange with pure nitrogen under pressure. This air fraction is then mixed with 55 the stream of impure nitrogen at the inlet of exchanger 3; the remaining air leaving the turbine is sent through pipe 12 to the central zone of low-pressure rectification column 16—17 which operates at substantially atmospheric pressure.

60 The column 15 and 16—17 are arranged in the usual manner; heat is exchanged indirectly between them by condenser-vaporiser 18. The bottom of high-pressure column 15 is heated by coil 44, in which some compressed nitrogen condenses. The air liquefied and enriched in oxygen collects at the bottom of this column and flows through pipe 22, passing through heat exchanger 23 counter-current to impure nitrogen and through expansion valve 24, to the middle part of column 16. A part of the impure nitrogen condensed in 65 condenser-vaporiser 18 serves as reflux in the high-pressure column; the other part is withdrawn through pipe 19, enters heat exchanger 20 where it flows counter-

current to gaseous nitrogen. It is then expanded through valve 21 before entering the low pressure column.

The low pressure column 16—17 is really composed of two parts having different diameters: lower end 16 and upper end 17.

The lower section of the low-pressure column 16 produces at its top impure gaseous nitrogen. It is withdrawn through valve 30, pipe 30A, exchangers 20 and 23, pipe 31 and exchanger 3. It then leaves the apparatus. At the bottom of column 16 oxygen is collected as follows and under the following conditions:

(a) Gaseous oxygen, which flows through valve 26, pipe 26A, exchanger 27 to pipe 28, and segment 5 of exchanger 3, before it is discharged through pipe 29; and

(b) Liquid oxygen, which flows through valve 25 and pipe 25A into segment 5 of exchanger 3, without passing through its colder section, and joins the stream of gaseous oxygen already mentioned. The object of this arrangement is to get additional cooling of the air before it flows through the cold section in accordance with the process described in French Patent No. 821,949 of May 18, 1937, and U.S. Patent No. 2,355,660 of August 15, 1944.

Upper end 17 of the low-pressure column is a zone for purifying nitrogen. As the quantity of pure nitrogen produced from the top is considerably less than that rising in lower end 16, it may have a smaller diameter, as shown on the drawing. The pure gaseous nitrogen at about —193° C. is removed through pipe 34, while the reflux of liquid nitrogen, expanded through valve 49, enters the top of the column.

The cold, gaseous, pure nitrogen in pipe 34 passes through exchanger 35, where it is warmed to about —173° C. by indirect heat exchange with liquid nitrogen under pressure. Then it flows through pipe 36 to reversing-exchanger 3. It passes through the cold end of this exchanger and then it is removed totally or partially, through valve 37 and pipe 37A at about —130° C. It is warmed by the compressed nitrogen to about 24° C., and, after combining with the nitrogen that has passed through the warm end of exchanger 3, it is compressed by compressor 39 to a pressure of about 15 to 30 kg./cm.².

A part of the compressed nitrogen can be removed through valve 40 and pipe 40A to be used in an adjacent plant, for example a liquid nitrogen scrubbing unit. The other part goes through pipe 41 into exchanger 38 where it is cooled to about —112° C. After combining with nitrogen at about —149° C. coming from the adjacent plant through pipe 40B, it passes through pipe 42 to exchanger 10 counter-current with the air going to expansion turbine 11 and which cools the nitrogen to —156° C. It leaves exchanger 10 through pipe 43, passes through exchanger 32 counter-current to impure nitrogen, exchanger 27 counter-current to oxygen, and finally through coil 44 in the bottom of high-pressure column 15 where it liquefies. The liquid nitrogen produced goes through pipe 45 to exchanger 14 counter-current to the part of the expanded air which joins the impure nitrogen, then through pipe 46 to exchanger 35 counter-current to cold pure nitrogen, which cools it to about —188° C. A portion of this liquid nitrogen is sent to the adjacent plant, for example to a nitrogen scrubbing column, through valve 47 and pipe 47A; the other portion goes through pipe 48 and expansion valve 49 to the top of low-pressure column 16—17 where it serves as reflux.

The plant thus described, besides operating economically, possesses great operating flexibility which allows it to be rapidly adapted to a broad range product requirements.

We claim:

1. A process for the purification and separation of air at low temperatures, comprising the steps of compressing said air, cooling it and depositing its high-boiling impurities in a heat exchange apparatus which reverses periodically the gaseous streams of air and of at least part of the separated nitrogen, liquefying and rectifying part of said compressed air in at least two rectification columns under successively lower pressures, expanding with external work another part of said air, warming the separated components of air by heat exchange with the incoming compressed air and reevaporating the deposited high-boiling impurities into at least said part of the separated nitrogen, warming another stream of nitrogen under 15 the lowest pressure by counter-current heat exchange with the incoming compressed air in the colder part of said heat exchange apparatus, compressing said other stream of nitrogen, cooling the compressed stream of nitrogen by heat exchange with said other part of air to 20 be expanded, at least partly liquefying it and introducing it into a rectification column as a reflux liquid.
2. A process according to claim 1, wherein at least part of the expanded air is blown into the rectification column under the lowest pressure.
- 25 3. A process according to claim 1, wherein part of the expanded air is warmed by heat exchange with said other stream of liquefied nitrogen, then is added to the separated gaseous nitrogen before it is warmed by counter-current heat exchange with the incoming compressed air.
- 30 4. A process according to claim 1, wherein said other stream of gaseous nitrogen under the lowest pressure, before being warmed by heat exchange with the compressed incoming air, is warmed by heat exchange with 35 said stream of at least partly liquefied nitrogen.
5. In a process for the purification and separation of air at low temperatures, wherein compressed air is cooled counter-currently to its separated components and its high-boiling impurities are deposited in a heat exchange 40 apparatus which reverses periodically the gaseous streams of compressed air and of at least part of the separated nitrogen, the said compressed air is at least partly liquefied and rectified in at least two rectification columns under successively lower pressures, and said part of separated nitrogen taken under the lowest pressure is warmed by counter-current heat exchange with the incoming compressed air, thereby re-evaporating said impurities, the 45 provement of warming another stream of gaseous nitrogen under the lowest pressure by counter-current heat exchange with said compressed incoming air in the colder part of said heat exchange apparatus, compressing said other stream of nitrogen and at least partly liquefying it, cooling it by heat exchange with said other stream of gaseous nitrogen under the lowest pressure to be 50 warmed in the colder part of said heat exchange apparatus, and introducing it into at least the uppermost part of the rectification column under the lowest pressure as a reflux liquid.
